US00D998765S

(12) **United States Design Patent** (10) **Patent No.:** **US D998,765 S**
(45) **Date of Patent:** **** Sep. 12, 2023**

(54) **ICE MELTING DEVICE**

(71) Applicant: **SHENZHEN GEDUO NETWORK TECHNOLOGY CO., LTD.**, Shenzhen (CN)

(72) Inventor: **Huan Wu**, Wuxue (CN)

(73) Assignee: **SHENZHEN GEDUO NETWORK TECHNOLOGY CO., LTD.**, Shenzhen (CN)

(**) Term: **15 Years**

(21) Appl. No.: **29/823,762**

(22) Filed: **Jan. 19, 2022**

(51) LOC (14) Cl. **23-03**

(52) U.S. Cl.

USPC **D23/314**

(58) **Field of Classification Search**

USPC D23/314, 328, 333, 354, 370-371, D23/377-383, 387, 392, 411-414, 320, D23/327, 329-330, 332, 335-350, 386, D23/398, 402-403, 324, 326, 353, 362; D14/402

CPC B60H 1/00; B60H 1/03; B60H 1/00264; B60H 1/0025

(57) **CLAIM**

The ornamental design for an ice melting device, as shown and described.

DESCRIPTION

FIG. 1 is a perspective view of an ice melting device, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines and areas within them depict portions of the ice melting device that form no part of the claimed design.

1 Claim, 8 Drawing Sheets
